ADJUSTABLE DEVICE FOR RELATING FACE-BOARD OF CURB MOLD TO BACKBOARD THEREOF**Eric E. Hogan and Robert S. Malloch, Riverside, Calif.****Application June 27, 1957, Serial No. 668,543****1 Claim. (Cl. 25—118)**

This invention relates to the art of assembling mold boards for forming a mold to cast a concrete curb and particularly to quickly demountable devices for relating the faceboard of the mold to the backboard thereof.

It is a particular object of the invention to provide such a device which may be readily employed to set up a mold and then to disassemble the latter without the use of any special tools.

It is another object of the invention to provide such a device which will accommodate itself without adjustment to faceboards varying substantially in breadth.

Devices of this character are generally made to support the faceboard in a given angular relation with the backboard of the mold. Thus an entirely different set of such devices is required where there is a change in this angle.

It is a further object of the invention to provide a device for relating the faceboard of a curb mold to the backboard thereof which is readily adjustable so that these devices may be set to give the desired angle between the faceboard and the backboard of the mold on any particular job in which these devices are used.

Board spacers heretofore employed extend directly across the top of the mold and thus offer some interference with the operations of the man finishing the upper face of the curb.

It is yet another object of the invention to provide such a board spacing device which will not interfere substantially with the operation of finishing the top surface of the curb.

The manner of accomplishing the foregoing objects as well as further objects and advantages will be made manifest in the following description taken in connection with the accompanying drawings, in which:

Fig. 1 is a fragmentary plan view of a curb mold in which a preferred embodiment of the invention is shown properly relating the faceboard to the backboard of the mold.

Fig. 2 is a vertical sectional view taken on the line 2—2 of Fig. 1.

Fig. 3 is an enlarged fragmentary vertical sectional view taken on the line 3—3 of Fig. 1 and illustrating the reverse face of the adjusting means of the invention.

Fig. 4 is a sectional detail view taken on the line 4—4 of Fig. 3.

Referring specifically to the drawings, the invention is illustrated therein as comprising a board spacing device 10 which is employed in relating the faceboard 11 of a curb mold 12 to the backboard 13 of said mold.

In the mold 12, the backboard 13 is always placed in vertical position on a graded surface 14 of the soil 15 on which the curb is to be erected. After the surface 14 has been graded and the backboard 13 placed upright in its proper position thereon, as shown in Fig. 2, a stake 16, which is preferably a steel rod of about three-quarter inch diameter and pointed at the lower end, is driven into the soil 15 to lie directly

2

back of the backboard 13 and in aligned contact with said board throughout the full height of the latter.

The device 10 is then placed over the upwardly extending end portion of the stake 16 and lowered onto the upper edge of backboard 13 as shown in Fig. 2. This device includes a stake clamp 20 having a U-shaped body 21, the latter being provided with aligned horizontal apertures 22 for receiving a shaft 23, one extending end of which is bent to form a handle 24 and the other extending end of which carries a head 25 which retains shaft 23 in place. This shaft is slightly bent so as to have an eccentric binding action when rotated as will be made clear hereinafter. A lock-bar 26 bent to form a long leg 27 and a short leg 28, is disposed within the U-shaped body 21 and has a keeper strap 29 welded thereto to form a loop through which shaft 23 extends, thereby retaining lock-bar 26 assembled on said shaft.

Welded to the front wall 34 of the body 21 is the lower end of a vertical leg 35 of an inverted U-shaped spacer bar 36, the other leg 37 of which extends at an obtuse angle downwardly to a point just above the upper edge of the faceboard 11 when the latter is properly positioned in the mold 12. The lower end of the leg 35 rests on top of the backboard 13 and is provided with a finger 34 which is welded thereto and extends downwardly to overlap the upper front corner of the backboard 13, as shown in Fig. 2.

Pivotedly mounted on the lower back corner of the spacer bar leg 37 is a faceboard jig 38. This jig includes a jig base 39 which comprises a vertical plate welded at its lower end to one edge of a faceboard jaw 40 which is adapted to embrace the upper edge of faceboard 11 as shown in Fig. 2. Welded to the opposite edge of the jaw 40 is a short metal bar 41 which cooperates with the plate 39 to form a shallow channel into which the lower end of the spacer bar leg 37 fits as shown in Fig. 3. When the leg 37 is thus related with the jig 38, a hole 42 formed in said leg is aligned with corresponding holes formed in the plate 39 and bar 41 and a bolt 43 is extended through these holes so as to pivotally mount the jig 38 on the spacer bar 36 on the axis of these holes. Group of holes 50 and 51, and group of holes 52 and 53, are also formed in the leg 37 with the holes of each group located at different radial distances from the axis of bolt 43 as clearly shown in Fig. 3. Holes 50 and 51 are formed at radius 54 from said axis while holes 52 and 53 are formed at radius 55 therefrom.

Also formed in jig base plate 39, at radius 54, is a hole 56, and at radius 55 is a hole 57. A bolt 58 is provided which is adapted to be extended through the hole 56 and either one of the holes 50 or 51 in leg 37; or bolt 58 is adapted to be extended through hole 57 and either one of the holes 52 or 53 in leg 37. The holes 50 and 51 are so related to the hole 56 and the holes 52 and 53 are so related to the hole 57 that this combination of holes provides an opportunity to set the spacer bar 36 relative to the jig 38 so that the latter will relate faceboard 11 in any one of four precise angular relations with the backboard 13 depending upon which combination of holes bolt 58 is inserted through. When the bolt 58 is thus inserted through any pair of holes provided in the jig base 39 and the spacer bar leg 37, a nut 59 is set on said bolt so as to rigidly unite the spacer bar 36 with the jig 38 with the latter in the angular relation exclusively produced by this particular combination of holes.

Welded to the front edges of the jig base 39 and jaw 40 is a faceboard guide tube 65. The upper end of this tube is disposed below the upper end of jig base 39 and the lower end of this tube terminates at a point above the lower edge of the faceboard 11. An oil hole 66 is provided in tube 65 for introducing oil. Slidably and rotatably mounted in the tube 65 is a rod 67 having a

lower faceboard gripping jaw 68 bent from the lower end thereof. The rod 67 extends upwardly from the upper end of tube 65, where it has a series of spaced holes 69 formed therein; through one of which a cotter 70 is inserted for trapping a coil spring 71, surrounding the rod 67, between said cotter and the upper end of tube 65. After the rod 67 has thus been assembled to extend through the tube 65 and spring 71, an upper end portion 73 of said rod is bent therefrom to form a handle.

Operation.

When the device 10 is moved downwardly over the stake 16, as shown in Figs. 1 and 2, the stake extends through the enclosed space 75 provided within the U-shaped body 21 so that the lock-bar 26 rests against the stake with spaced sharp corners directly engaging the latter. The vertical dimension of the body 21 is approximately 1 1/4 inches and when the clamp 20 is positioned on stake 16 as shown in Figs. 1 and 2 and the handle 24 turned to rotate the shaft 23 to effect an eccentric-like binding action against the lock-bar 26, the sharp corners of the latter are pressed against the stake 16 to lock the latter in a vise-like grip against the front wall 34 of the body 21. This action unites the body 21 with the stake 16 so as to practically prevent any rotation of the device 10 relative to the stake 16 in the plane of the drawing. The device 10 is thus given a rigid cantilever support on the stake 16 and backboard 13.

It is assumed of course that, prior to starting the assembly of mold 12, the bolt 58 has been selectively placed in the proper pair of holes in the spacer bar leg 37 and jig base 39 to cause the faceboard 11 to be given the proper angular relation with backboard 13 when the faceboard 11 is assembled in the jig 38. The latter step is accomplished in the following manner.

With the stake clamps 20 rigidly locked on the stakes 16 as above described, the faceboard 11 is lifted by the mold assembling crew and the lower edge of the faceboard is rested on the jaws 68, which are turned toward this board in the same direction they are shown as disposed in Fig. 2. The board 11 is now pressed downwardly to compress the spring 71 until the upper edge of the faceboard 11 lies below the upper jaw 40 of the jig 38. The faceboard 11 is now rocked towards and into flush contact with the guide tube 65 whereupon downward pressure on the board 11 is relaxed, allowing the springs 71, of the various devices 10 in the mold 12, to lift the faceboard 11 until its upper edge reposes in the upper jaw 40 of the jig as shown in Fig. 2.

With the mold thus assembled it is ready for the pouring of concrete which fills the space within the mold up to the broken lines 80 and 81, it being the common practice to simultaneously cast a curb and gutter as an integral structure. When the concrete thus cast has set sufficiently to retain its form, and this takes place in a relatively few minutes, the mold 12 may be disassembled.

To do this, the crew members walk along the mold, pressing down manually on the handle 73 of each of the devices 10 so as to compress its spring 71 and lower the jaw 68 out of contact with the bottom edge of the faceboard 11, whereupon the crew member rotates the rod 67 by turning the handle 73 through an angle of 180° which brings the jaw 68 into the broken line position 90 in which this is shown in Fig. 2. The crew member then relaxes downward pressure on the handle 73 allowing the spring 71 to lift the jaw 68 above the concrete sur-

face 81. The crew member now turns the handle 24 of the stake clamp 20 in a reverse direction from that in which it was turned to set the clamp on the stake 16, thereby relaxing the hold of the clamp on the stake and permitting the lock-bar 26 to be pushed upward and backward so that it hangs down from the shaft 23 out of operative contact with the stake 16. The device 10 is now completely freed from the faceboard 11, backboard 13, and stake 16 and may be lifted directly upward off of said stake.

The devices 10, thus removed, are free to be transported immediately to an advance section of the curb molding job and re-employed in setting up an extension of the mold 12.

While only a single preferred embodiment of the invention has been disclosed herein it is to be understood that various changes and modifications may be made in this without departing from the spirit of the invention or the scope of the appended claim.

The claim is:

An adjustable device for optionally fixing the faceboard of a curb mold in any one of a plurality of precise angular relations with the backboard of said mold, said device comprising: a steel stake driven vertically a substantial distance into the soil, when in use, in flush contact with the back face of said backboard, a portion of said stake extending above said backboard; a stake clamp having a vertical opening for receiving said upwardly extending portion of said stake and manually operative to grip said stake so tightly as to render the clamp immovable relative to said stake; a spacer bar integrally united with said clamp and extending therefrom to a horizontal line parallel with said backboard and disposed just above the upper edge of said faceboard when the latter is located in any of said precise relations with said backboard; means on said device for engaging said backboard to hold the latter against said stake; a jig for gripping said faceboard, said jig including a body providing a guide against which an outer face of said faceboard rests when the latter is held in said jig, a jaw integral with said body against which an upper edge of said faceboard rests when the latter is held in said jig, a lower jaw shiftably provided on said body, and manually operable means on said jig for shifting said lower jaw between a position away from beneath said faceboard and a position therebeneath, and then toward said faceboard to clamp the same between said jaws, said means then retaining said faceboard so clamped; pivot means for pivotally uniting said jig body and said spacer bar on said horizontal line; and plural adjustment holes and bolt means for optionally uniting said jig body to said spacer bar in any one of a plurality of precise angular rotational positions about said line relative to said bar, each of said positions causing said jig to hold said faceboard in a particular one of said precise angular relations with said backboard.
